UNITED STATES PATENT OFFICE.

JOSEPH AMEDEE GASSE, OF BROCKTON, MASSACHUSETTS.

GATE-CONTROLLING MECHANISM FOR RAILROADS.

1,142,319.

Specification of Letters Patent.

Patented June 8, 1915.

Application filed September 12, 1911. Serial No. 648,939.

To all whom it may concern:

Be it known that I, JOSEPH AMEDEE GASSE, subject of the King of Great Britain, residing at Brockton, in the county of Plymouth and State of Massachusetts, have invented certain new and useful Improvements in Gate-Controlling Mechanism for Railroads, of which the following is a specification.

The primary object of my invention is the provision of a simple, automatic, electrically operated means for controlling the gates of railway crossings, so arranged that on the approach of a train the gates will be automatically closed and that after the train has passed the gates will be automatically opened.

Another and most important object of this invention is to provide gates that will automatically operate at every hour of the day and night, thus obviating a trouble found on unimportant branches of a good many railroads where gate tenders only work until 9 p. m. and the gates remain in their raised position from that hour until the following morning.

A further object is to so construct the mechanism for operating the gate that it may be used with the ordinary form of railway gate at present customarily used by almost all roads, that is, a gate having a counterweighted arm held normally in a vertical position but rotated to a horizontal position across the road to guard the same upon the approach of a train.

Other objects will be disclosed in the accompanying description.

An embodiment of my invention is illustrated in the accompanying drawings wherein:

Figure 1 is a cross sectional view of the wagon road showing the gate in its lowered position, the supporting casing for the gate being broken away. Fig. 2 is an enlarged section of the casing supporting the gate arm, the figure showing the internal parts and the section being taken on the line 2-2 of Fig. 3. Fig. 3 is a section on the line 3-3 of Fig. 2. Figs. 4 and 5 are detail views of the mechanism for breaking the circuit through the motor when the arm has descended to its lowered position or been raised to its vertical position. Fig. 6 is a detail face view of the gear wheel 6 on the crank shaft 6^a. Fig. 7 is a sectional view

of one of the boxes containing the motor controlling mechanism, said mechanism being shown in elevation. Fig. 8 is a section on the line 9-9 of Fig. 7. Fig. 9 is a sectional view of one of the boxes containing the motor actuating mechanism, the front elevation of the actuating mechanism being illustrated. Fig. 10 is a fragmentary detail view of a portion of the actuating shaft, the ratchet wheel thereon and an inside face view of the gear wheel by which the shaft is actuated. Fig. 11 is a perspective detail view of the switch whereby the motor circuit is closed or broken. Fig. 12 is an electrical diagram showing the wiring for one of the switch actuating devices. Fig. 13 is a wiring diagram showing the connection between a plurality of actuating devices and the motor.

Corresponding and like parts are referred to in the following description and indicated in all the views of the accompanying drawings by the same reference characters.

My improved mechanism is designed to be used preferably where there are two parallel tracks and passage across the tracks is controlled by means of gates disposed on each side of the tracks. Erected between the tracks are the gate motor actuating devices C, D, E and F as will be later described.

Each gate is of the type ordinarily used on railways, consisting of a supporting casting 2, an arm 3 counterweighted by a weight 4. In this type of railway gate the pivot shaft of the arm usually carries upon it a pinion which meshes with a toothed gear operated by means of a crank. A like gate is provided on the opposite side of the railroad track which is geared with the first named gate and operates simultaneously therewith. As the connection between the gate on one side of the tracks and the gate on the opposite side is old and well known and not part of my invention, I have not illustrated it nor do I deem it necessary to more than refer to it.

Referring now more particularly to Figs. 1, 2 and 3, it will be seen that the arm 3 is mounted upon a pivot shaft 5 and that also mounted on this shaft is a toothed gear wheel 5^a which meshes with a gear wheel 14. Mounted on a parallel shaft 6^a is a fly wheel 5^b, and also mounted on this shaft is a toothed gear 6 which has a certain rotative

play upon the shaft 6^a. To this end the gear 6 is loose on the shaft 6^a and the central passage for the shaft is cut away on one side to provide a recess 7 having opposed shoulders 8 and 9 as shown in Fig. 10. The shaft is formed with a lug or pin 10 projecting into this recess and adapted to engage one or the other of the shoulders 8 or 9. It will be seen that the gear wheel 6 10 may thus have independent rotation through a short distance before this rotation is communicated to the shaft 6^a and to the gate arm.

The gate is operated by means of an electric motor 11 of any suitable construction, the shaft 12 of which carries a pinion 13 meshing with the toothed gear 6 on the shaft 6^a. While I have shown this particular form of gearing for transmitting motion from the motor to the pivot shaft 5, I do not wish to be limited to this specific arrangement as it is obvious that other means for communicating said motion might be provided. Also mounted upon the shaft 6^a and rotatable therewith is a ratchet wheel 15 having ratchet teeth upon its circumference. Mounted upon the side wall of the casing 2 or in any suitable manner is a pawl 16 adapted to engage the ratchet teeth on the wheel 15 and prevent any rotation of the ratchet wheel in the direction of the arrow, Fig. 2. This pawl is normally held in engagement with the ratchet wheel by means of a spring 17 or in any suitable manner.

Provision must of course be made for raising the pawl 16 out of its engagement with the ratchet wheel prior to the rotation of the shaft 5 and the gate arm. For this purpose I provide an interrupted ring or like member 18 which as shown is carried upon the face of the gear wheel 6. This ring as illustrated in Fig. 6 is interrupted at three points. One termination of the wall forming the ring at each gap is provided with a pivoted gate 19 while the adjacent termination of the opposed end of the wall is formed with an inwardly extending inclined deflecting portion 20.

Pivoted in any suitable manner adjacent to the pawl 16 is a lever 21, one end of which is provided with a nose 22 engaging with the pawl 16. The other end of the lever 21 extends inward and is provided with a stud 23 engageable by the deflecting members 19 and 20. When the gate is in its vertical position, this stud 23 is on the inside of the ring 18. As the gate rotates, however, in the direction of the arrow in Figs. 2 and 6, the stud will come in contact with the deflected portion 20 and will be guided out through the opening 24 to the outside of the ring, thus moving outward the outer end of the lever 21 and lifting the pawl 16 from its engagement with the

ratchet teeth. Upon a reverse movement of the gear wheel 6, the stud 23 will be engaged by one of the deflectors 19 and will be shifted inward, thus releasing the pressure upon the pawl 16 and permitting the spring 17 to throw it in engagement with the ratchet. It will be seen that the ring 18 with its deflected portions 19 and 20 will act to shift the pawl 16 out of engagement as the arm is lowered and into engagement with the ratchet as the arm is raised. The pawl 16 being contained within the casing 2 cannot be meddled with and prevents any accidental or malicious depression of the gate.

It will be seen that the gear attached to the shaft 6^a will make several turns. As the gear revolves it will carry with it the attached ring 18 (see Fig. 6). Inasmuch as the members 19 are pivoted, they will make a smooth rolling surface for the stud or roller 23 which when traveling outside of ring 18 holds the pawl 16 in its raised position. When the stud or roller 23 travels inside the ring it is relatively loose and can easily follow the deflection made by members 20.

A source of energy is of course provided for the motor. This source may be either a battery, or the energy may be carried along a line wire and delivered to the motor. The circuit to the motor, however, is normally broken when the gate is in the position shown in Fig. 2. Upon the approach of a train, however, the circuit is completed through the motor, thus energizing it, and the rotation of the motor acts to depress the gate. Just before the gate has reached its fully depressed position, the motor is thrown out of circuit with the source of energy and the gate descends by its own impetus. After the train has passed, a circuit is again closed through the motor and the source of energy, only the direction of the current is reversed to that in the first instance and the motor is reversely operated, thus raising the gate. The gate continues to rise until it is nearly in a vertical position, whereupon the circuit through the motor is again broken and the gate reaches its vertical position under the impetus of a fly wheel 5^b. The means whereby this is accomplished is as follows: Mounted alongside or between the tracks but preferably between the tracks are the actuating members (shown in Figs. 7, 8 and 9). There are four of these members, two to control the gates upon the passage of a train in one direction and two to control the gates upon a passage of a train in an opposite direction. The members C and E operate together for a train going in one direction, while the members D and F operate together for a train passing in the opposite direction. The mechanism forming part of the actuating member C operates the gate upon the approach of a train on one track 130

while the mechanism E raises the gate upon the passage of a train upon the same track. The actuating member F operates in conjunction with the train approaching upon the second track in one direction and the member D acts to actuate the motor of the gate to raise the gate upon the passage of a train on the second track away from the crossing.

10 It is particularly to be understood that on a single track one set of actuating mechanism has its arms 28 extending upward while on the other set the arms extend downward, thus providing that a train coming from one direction upon the single track will be able to actuate one pair of actuating devices but not the other, and vice versa.

15 The actuating mechanisms for closing the circuit through the motor and operating the motor to lower the gate are located at any suitable distance on each side of the roadway crossing the railroad track. The distance of course is to be determined by the 20 average speed of trains passing this crossing, and the actuating devices are to be located so far from the cross roads that ample time will be given for the closing of the gate before the arrival of the train at the cross roads. The actuating mechanisms C, D, E and F all have the same construction and hence a description of one will apply to all. The actuating mechanism is preferably mounted on a post 25 which carries upon its 25 upper end a casing 26 shown in Fig. 7. Passing through this casing is a shaft 27 upon which is mounted an arm 28, this arm being mounted exteriorly of the casing 26.

20 Disposed within the casing is a supporting member 29 of any suitable character, and mounted in this supporting member are a pair of electro-magnets 30. Also mounted upon the supporting member 29 are the downwardly extending brackets 31 between which is pivotally supported a shaft 32. Mounted on the shaft are the parallel arms 33 carrying on their extremities the armature 34 which coacts with the cores of the pair of electro-magnets 30. Fast upon the 25 shaft 27 is a segment wheel 27^a having a grooved periphery and over which passes a flexible connection 36 whose depending end is connected in any suitable manner to a cross piece 37 connecting the arms 33. It will be obvious that when the shaft 27 is rotated the frame formed by the arms 33 and the cross piece 37 will be raised, thus bringing the armature 34 into engagement with the cores of the magnets 30. These magnets 30 are connected in circuit with a battery 35 (see Fig. 12). When the armature 34 is in contact with the cores of the energized magnets 30 it will be obvious that the armature will be held in its raised position by virtue 30 of the attraction of the electro-magnets.

35 Mounted upon the depending brackets 31 is a supporting member 38 upon which is mounted the spaced contact members 39, 39^a. These contact members 39, 39^a are adapted to contact with a pair of spaced contact members 40, 40^a carried upon the frame formed by the arms 33 and the cross piece 37. Each contact member 39, 39^a is connected by a wire to the commutators of a motor 11, while each of the contact members 40, 40^a is connected by a wire 43 to each other and each in turn connected to the battery 35 as will be more fully described later.

40 It is to be noted that the magnets 30 are normally energized and that when the frame 35 formed by the arms 33 is raised, the armature 34 will be placed in engagement with the cores of the magnets 30 and will be held against these cores by the attraction exerted by the magnets, and that in this position the contacts 39 and 40 and 39^a and 40^a will be closed, thus completing a circuit through the motor as will be later described. Precisely the same mechanism is used for all of the actuating devices, C, D, E and F.

45 In the wiring diagram illustrated in Fig. 12, I show the connection of one of the actuating devices with the motor and with the storage battery or other source of energy. This figure is simply a diagram to show the 50 means for closing the motor circuit upon an actuation of one of the actuating devices and the means for breaking the circuit just prior to the time that the gate either rises or falls to its vertical or horizontal positions, 55 the reversing means not however being shown, the reversing mechanism being illustrated in Fig. 13. From this diagram it will be seen that the contact 40 is connected by conductors 51 and 52 to the field magnets of 60 the motor, which in turn are connected in circuit with the battery 35 by the conductor 53. From this battery 35 current is carried along the conductor 54, thence by the conductor 55 to the contact 40^a, thence to contact 39^a, thence by a conductor 56—57—58^b to one of the commutators of the motor 11, thence through the motor to the other commutator and to connection 58^a, thence to the conductor 59 and conductor 60 back to the 65 contact 39, and thence to contact 40, thus completing a circuit through the battery and motor and starting the motor. So long as this circuit is completed, so long will the motor operate. When, however, the circuit is broken, as by the removal of the contacts 40 and 40^a from electrical connection with the contacts 39 and 39^a, then the motor will stop.

70 For the purpose of holding the circuit closed until the gate arm has reached its terminal position, I provide the electro-magnet 30 coacting with the armature 34. This electro-magnet is in a normally closed circuit with the battery 35, through con-

ductor 61 to conductor 53, thence through the battery, thence by conductors 54 and 62^a to the arcuate conducting strips 70, 66 and 65 to conductor 68, thence back to magnet 30, thus completing the circuit through the electro-magnet and the battery. So long as this circuit is unbroken, the magnet will hold the armature 34 against its cores and will hold the motor circuit closed. When, however, the magnet circuit is broken, as will be now described, the magnet 30 is deenergized, permitting the armature 34 to drop, thus breaking the motor circuit. The circuit breaking device for the magnet circuit is as follows: Mounted upon the shaft 5 is the arm 62 and loosely pivoted upon the extremity of the arm 62 is a link 63 carrying upon its extremity the outwardly projecting stud 64. Mounted concentrically to the shaft 5 are the arcuate guide strips 65 and 66 which are in electrical connection with each other at one end by means of a hinged contact member 67. The contact strip 65 is electrically connected to the conductor 68 which runs to the magnet 30 as illustrated in Fig. 4. The contact member 67 is pivoted preferably to the extremity of the contact strip 65 and normally bridges the gap and closes the circuit between the strips 65 and 66, the contact member being held in this position by means of a spring 69.

Extending parallel to the contact member 66 is the arcuate contact member 70. It will be noted that the member 65 projects at its lower end beyond the member 66, while the arcuate strip 70 projects at its upper end beyond the strip 66. The gap between the lower end of the strip 70 and the adjacent end of the strip 66 is bridged and the circuit closed by means of the pivoted contact member 67^a which is held in its normal position by means of its own weight. The contact member 70 is connected by the conductor 62^a to the battery 35.

When the gate is in a vertical position, the parts are in the position illustrated in Fig. 4 and the magnet 30 is energized by the battery. When the armature 34 is raised in contact with the electro-magnets 30 it will be held in its raised position by the attraction of the magnets and, as before explained, the motor will be started. As the motor operates, the shaft 5 will be turned in a counter-clockwise direction and the stud 64 will be carried along between the strips 65 and 66 (see Fig. 4). When the arm 62 has nearly reached a horizontal position and the gate arm 3 has nearly descended to its full extent, the stud 64 will open the pivoted contact member 67 and break the circuit through the magnets 30. This circuit will remain broken until the gate has descended so far that the stud escapes the contact member 67

which will drop back into position, thus again closing the circuit through the magnets 30 and energize the same. The gate is now lowered by the impetus given to the fly wheel 5^b and the link 63 will swing to the position shown in Fig. 5. Now if the arms 33 of the actuating device E be raised the circuit will once more be completed through the motor in precisely the same manner as before described only the current will pass in a reverse direction, thus reversing the direction of the motor. The arm 62 will now descend and the stud 64, when the arm has nearly reached its vertical position, will open the contact member 67^a, thus again breaking the circuit through the magnets and allowing the arms 33 to drop and break the circuit through the motor. When the arm 62 has reached its fully vertical position, the link 63 will again take the position shown in Fig. 4 and be ready for the next actuation of the gate.

In Fig. 13 I show the four actuating devices, C, D, E and F, each connected with the motor, the conductors 56, 55, 61 and 60 being distinguished from each other by the exponents *c*, *d*, *e* and *f*, the line wires connecting all of the actuating devices to the motor and battery being designated 54, 57, 59, the line wires forming the magnet circuit to all the magnets and the battery being designated 54, 66'.

It will be understood that the actuating device C is to actuate the motor to close the gate for a train entering on one track and the actuating device E is for reversely actuating the motor by the same train. The actuating device F is to actuate the motor to close the gate by a train arriving from the opposite direction on the other track and the actuating device D is for reversely actuating the motor to raise the gate upon the passage of said last named train beyond the crossing.

By referring to Fig. 13, it will be noted that under normal conditions, that is, when the gate is either fully lowered or fully raised, a circuit will be formed through the battery and the electro-magnets 30 of all of the devices C, D, E and F. This circuit passes through the wire 54 to the electro-magnet 30^c, from this electro-magnet through the wire 66 to the electro-magnet 30^e and from this electro-magnet to the contact 65 of the gate controlled circuit breaker, from the contact 70 of such circuit breaker to the electro-magnet 30^d, from this electro-magnet by means of the wire 66' to the electro-magnet 30^e and from this electro-magnet by the wire 61 back to the wire 53 and so to the battery.

In operation, a train approaching the road crossing from one direction will engage the actuating arm 28 of the device C raising

the armature 34 of such device into engagement with the magnet 30 which, being normally in a closed circuit, holds the armature in raised position closing circuits between 5 the contacts 39 and 40 and 39^a and 40^a of such device. Under these conditions, current flows from the battery through the wire 54 to the contact 40^a, from the contact 39^a through the wire 56^a, wire 57 through 10 the motor 11, from this motor through the wire 59 and 60^a to the contacts 39 and 40 and from these contacts through the wire 51^a to the field winding of the motor and from such winding back to the battery. 15 Under these conditions, the motor 11 will be rotated to lower the gate until the circuit of the electro-magnet 30 is broken by momentary opening of the gate operated circuit breaker, illustrated in Fig. 5. When 20 the train passes the device D, the armature of such device is raised to close circuit between its contacts, under which conditions, current will flow from the battery through the wire 54 and wire 55^a to the contacts 40^a 25 and 39^a, from these contacts through the wire 56^a and wire 59 to the motor 11, passing through this motor in a direction reverse to that previously described, from this motor through the wire 60^a to the contacts 39 and 40 of the device D, from these contacts 30 through the wire 51^a and through the field winding of the motor back to the battery. This will cause opposite rotation of the motor 11 and consequent raising of the gate, 35 the motor continuing to operate until the gate actuated circuit breaker again momentarily breaks the magnet circuit. On the other hand, a train approaching in the opposite direction will raise the armature of 40 the device F to close a circuit from the battery through the wire 54 and wire 55^a to the contacts 40^a and 39^a, from these contacts through the wire 56^a through the motor in the same direction in which the circuit 45 passed from the device C, from the motor through the wire 60^a to the contacts 39 and 40 of device F and then through the wire 51^a to the field winding of the motor and so back to the battery. This will cause the motor 50 to rotate to lower the gate, this rotation continuing until the gate controlled breaker momentarily opens the magnet circuit. Again, when the train passes the device E, raising its armature, a circuit is formed 55 from the battery through the wire 54 and wire 55^a to the contacts 40^a and 39^a of device E, from these contacts through the wire 56^a to the motor 11, passing through the motor in the reverse direction to that of the circuit 60 from the device F, from this motor through the wire 60^a to the contacts 39 and 40 of device E and from these contacts through the wire 51^a to the field winding of the motor and back to the battery. This cir-

cuit reverses the direction of rotation of the 65 motor and drives the same until the circuit is broken by the gate controlled circuit breaker.

The actuating devices C, D, E and F are each provided with the downwardly depending arm 28 attached to the shaft 27. The locomotive is provided with an outwardly projecting arm which is so placed as to engage with the depending arm 28 and raise the arm to a horizontal position, thus turning the segment wheel 27 and raising the frame formed by the arms 33 and the cross bar 37. The parts are held in this position by the attraction of the magnet 30 for its armature. The locomotive arm may be 80 raised or lowered into or out of operative position in any suitable manner. When the train has passed the roadway over which the track crosses, the arm will strike the depending arm 28 of the actuating devices D or E 85 (depending upon which way the train is going) and the gate will be raised.

It will be understood of course that I do not wish to limit myself to the precise construction illustrated as different constructions might be used which would attain the same end, though I believe that the construction devised is the most practical for the purpose of securing the advantages of my invention.

What I claim is:

1. In combination a railway gate, a shaft for operating the gate, a gear wheel loosely mounted upon the shaft, means for engaging the shaft and gear wheel after a partial rotation of the gear wheel, means for holding the shaft from rotation in one direction, and means operated by a partial rotation of the gear wheel for releasing said holding means and permitting the gate to operate.

2. In combination a shaft, a gate arm operable by the shaft, a gear wheel loosely mounted upon the shaft, the gear wheel being formed with a recess having opposed shoulders and the shaft having a stud projecting into said recess and engageable with one or the other of said shoulders to positively connect the gear wheel with the shaft, a ratchet wheel on the shaft, a pawl engaging the ratchet wheel for preventing a return movement of the shaft, and means mounted on the gear wheel for lifting said pawl upon a partial rotation of the gear wheel.

3. In a railway gate, the combination of a shaft, a gate arm operable by the shaft, a gear wheel mounted on the shaft and having a recess provided with oppositely disposed shoulders, a stud projecting from the shaft and engaging in said recess, a ratchet wheel mounted on the shaft, a pawl engaging the ratchet wheel, means on the gear wheel for raising the pawl upon a partial rotation of

the gear wheel, a motor geared to said gear wheel, a source of energy connected in a normally open circuit with the motor, means operated by a train for closing said circuit and energizing the motor to operate the gate arm, and means for breaking said circuit as the gate nears its terminal position.

4. In a railway gate, a motor operatively connected to the gate to raise and lower the same, a source of energy, a normally open circuit including the motor and the source of energy, a switch movable in one direction to close said circuit and energize the motor, train operated means for shifting said switch to close the circuit, an electro-magnet acting to hold the switch in its closed position after it is shifted, a normally closed circuit connecting the electro-magnet to the source of energy, and a circuit breaking device located in said last named circuit and operated in connection with the gate and comprising a plurality of spaced contact strips connected in the magnet circuit, pivotally mounted contact members electrically connecting said strips, means movable with the gate for shifting said contact members to temporarily break the circuit as the gate nears either of its terminal positions.

5. The combination with a gate arm, a motor for actuating the gate arm, a source of energy connected in circuit with the motor, and a circuit breaking device mounted in said circuit, of a magnet for holding said circuit breaking device in position to close said circuit, parallel spaced arcuate contact strips, said strips being connected in circuit with the magnet and the source of energy, oppositely disposed members pivoted to said strips and normally electrically connecting the same in closed circuit with the magnet and the source of energy, a link freely pivoted to the gate arm and depending therefrom and having a stud at its lower end extending between said strips, said link being shiftable with the gate arm to temporarily shift the pivoted contact members to break the circuit through the source of energy and the magnet as the gate arm reaches either one of its terminal positions.

In testimony whereof, I affix my signature in presence of two witnesses.
